UNITED STATES PATENT OFFICE

2,153,401

ELECTRIC SWITCH

John F. Tittle, Erie, Pa., assignor to General
Electric Company, a corporation of New York

Application September 29, 1937, Serial No. 166,277

7 Claims. (Cl. 200—154)

My invention relates to switches for controlling electric circuits and has for its object a simple and reliable manually operated switch.

More particularly, my invention has for its object a manually operated switch which is provided with snap acting means for moving the switch between its closed and open positions with a snap action, and also with a permanent magnet for extinguishing the arc.

10 In carrying out my invention in one form I provide an operating member made of electrically insulating material which is pivotally mounted for movement between its closed and open circuit positions. Snap operating means are 15 provided by a projection on the operating member near its pivot with a spring member near the projection and a link member between the projection and spring member whereby a snap acting toggle is formed.

20 Another feature of my invention is the simple and effective mounting of the movable contact on the operating member. This consists of a spring between the operating member and the support which holds the movable contact arm 25 on the operating member, and a projection forming a pivot for the contact arm when it engages the stationary contact.

Magnetic arc blow-out means is provided by means of a permanent magnet in the form of a 30 straight bar which is mounted adjacent the fixed contact so as to extend in a direction perpendicular to the plane of movement of the movable contact. This bar magnet is made of a material having a high coercive force and the magnet operates to effectively extinguish the arc while being extremely simple and compact.

This straight bar type arc-extinguishing magnet is of especial advantage where a plurality of switches are used. In accordance with my invention these switches are mounted in side by side relation with their stationary contacts in alignment and an arc-extinguishing magnet is provided consisting of a single bar extending adjacent the fixed contacts.

45 This magnetic arc blowout means is claimed in my copending divisional application, Serial No. 216,790, filed June 30, 1938.

For a more complete understanding of my invention reference should be had to the accompanying drawing of which Fig. 1 is a plan view of a group of switches embodying my invention; Fig. 2 is a side view of the device shown in Fig. 1; Fig. 3 is a sectional view along the line 3—3 of Fig. 1; Fig. 4 is a sectional view along the line 4—4 of Fig. 1, but showing the switch in the closed

circuit position; while Fig. 5 is a fragmentary view showing a modified form of my invention.

Referring to the drawing, I have shown my invention as applied to a group of manually operated switches which are identical in construction, 5 four switches being shown, each being provided with an operating member 10. As shown in Fig. 3, the operating member 10 is made of a suitable electrically insulating material which preferably is a molded composition. It is provided with a projection or handle 11 which may be grasped to turn it about a pivot shaft 12 on which the member is mounted.

The member 10 is provided with a second projection 13 which, as viewed in Fig. 3, extends 15 downward from a point adjacent the pivot shaft 12. This projection 13 engages the supporting base 14 when the operating member is in the open circuit position. On its lower end, the projection 13 is provided with a groove or recess 20 15 which forms a bearing for one end of the link member 16, the other end of which rests in a bearing seat 17 formed for it on the end of a cantilever spring 18. The other end of the spring is secured to the base 14 by means of a bolt 19. 25 The link 16 and the projection 13 thus constitute a toggle, the movable pivot point 15 between them moving from one side to the other of a line joining the center of the shaft 12 with the bearing 17 so as to thereby give the member 10 a snap 30 action and hold the member 10 in either the open position as shown in Fig. 3 or the closed position shown in Fig. 4.

The movable contact 20 of the switch is secured to the end of an electrically conducting strip 21 35 having near its center a loop or recess 22 formed by bending it. This loop 22 forms a bearing for a projection 23 on the operating member 10. The strip 21 is secured in place by means of a pin 24 extending loosely through an aperture provided for it in the strip on the side of the loop 22 opposite the contact 20, and also loosely through an aperture provided for it in the operating member 10. A head 25 is provided on the pin which head engages the strip 21 and furthermore forms a seat for one end of a helical spring 26, the other end of which surrounds the head 27 of the bolt 19. A flexible conductor 28 connects the strip 21 with a short terminal strip 29 which is clamped to the base 14 by the bolt 19, the lower end of the spring 26 resting on this strip 29. In addition to its other functions the bolt 19, which is preferably made of a suitable electrically conducting material such as steel or 55

copper, serves as a terminal for the switch to which an electrical connection may be made.

The stationary contact 30 of the switch is mounted on a block 31 of electrical conducting material such as brass or copper in position to be engaged by the movable contact 20, this block being in turn secured to a terminal conductor or strap 32. Preferably as shown, the block 31 is formed integrally with the strap 32. The block 31 is furthermore provided with an aperture 33 for a rod or bar 34 made of a suitable magnetizable material and serving as a magnetic blow-out device for the arc formed between the contacts 20 and 30.

15 The magnetic bar 34 is made of a material having a high coercive force preferably an alloy consisting mainly of aluminum, nickel and iron, preferably aluminum 12%, nickel 25%, the balance being mainly iron, such as described and claimed in Patent No. 1,947,274, issued February 13, 1934, to William E. Ruder and Patent No. 2,027,994, issued January 14, 1936 to Tokushichi Mishina. I have found that very effective blow-out action is obtained with a magnetized rod or bar of this material arranged as shown in the drawing near the stationary contact, but on the side of the stationary contact opposite from the movable contact, and having its axis extending at right angles to the arc drawn between the contacts or as shown at right angles to the plane of movement of the movable contact.

In the assembly of a plurality of switches as disclosed, the various blocks 31 forming the supports for the stationary contacts are formed integrally with and in suitable spaced relation to the supporting strap 32. Barriers or arc chute members 35 made of a suitable electrically insulating material, such as building lumber, are put in place between adjacent blocks and then the magnetized rod 34 is inserted in the blocks and through suitable apertures provided for it in the arc chute members 35. An additional arc chute member 36 is provided at each end of this assembly, the rod 34 being long enough to extend through these two outer members. A rectangular pole piece member 37 made of a suitable non-magnetizable magnetic material, such as magnet core iron, is secured against each end of the bar 34 by screws 38 which also secure the arc chute members 36. This assembly is secured to the insulating base 14 by means of bolts 39 and 40 extending through the ends of the strap 32. As shown, the base 14 is cut away to leave a rectangular opening 41 for this assembly of the contacts, arc chutes and magnetized bar. One or both of the bolts 39 and 40 may be used as a common terminal for the switch, or terminals on the members 31 may be provided.

As shown, the operating members 10 are mounted on a common pivot bar 12 which is secured by means of one or more brackets 42 to the base 14 in suitably spaced relation thereto.

Obviously more than four switches can be secured together in a group and I have in fact disclosed for purposes of illustration one end only of an assembly of several groups of these switches.

In the operation of the switch it will be observed that the supporting strip 21 for the movable contact is held in place by the helical spring 26 and furthermore when the movable contact engages the stationary contact the spring 26 yields to provide for pivot movement of the strip on the projection 23 in a clockwise direction as seen in Fig. 3, the strip coming to rest against the outer end of the member 10, as shown in

Fig. 4. This movement of the movable contact provides for a wiping action on the stationary contact whereby a good electrical engagement between the contacts is assured. To further provide for this wiping action the cantilever spring 5 18 is constructed to apply a greater force to the member 10 tending to close it than the force applied in the opposite direction by the spring 26.

It will be understood that the member 10 is forcibly moved by means of the handle 11 in both the opening and closing directions through an angle sufficient to bring the pivot point 15 to the other side of the toggle straightened position whereby the force exerted by the spring 18 is reversed and the opening or closing movement of the switch is completed by the spring 18.

The pivot movement of the strip about the projection 23 is furthermore somewhat greater than the movement of the member 10 required to reverse the force supplied by the spring 18 and consequently the contacts are separated by the snap action thereafter produced by the spring 18.

It will be observed that a second projection 43 is provided on the member 10 adjacent the pin 24 but on the side of the pin opposite from the projection 23. This projection provides a pivot for the strip 21 in the event that the stationary contact is provided above the movable contact as shown in Fig. 5, whereby a wiping action is obtained.

It will be understood that for less severe circuit controlling conditions the permanent blow-out magnet may be omitted, and also when practicable an electromagnetic blow-out coil connected in the switch circuit may be used instead of the permanent magnet.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

What I claim as new and desire to secure by Letters Patent of the United States is:

1. A switch comprising an operating member, a support, means pivotally mounting said member on said support for pivotal movement between open and closed circuit positions, a handle on said member, a switch contact, a conducting strip supporting said contact, a projection on said operating member forming a bearing for said strip, a spring between said operating member and said support for holding said strip on said operating member, a stationary contact secured to said support in position to be engaged by said movable contact when said operating member is moved to its closed circuit position, said strip moving on said projection as a pivot against the force applied by said spring to provide a wiping action upon engagement of said contacts.

2. A switch comprising an operating member made of insulating material, a support, means pivotally mounting said operating member on said support in substantially parallel relation therewith for pivotal movement between open and closed circuit positions, a handle on said operating member, a switch contact, a conducting strip supporting said contact, said strip being provided with an intermediate recess forming a bearing, a projection on said operating member engaging said bearing, a helical compression spring mounted between said operating

member and said support, a pin extending through said strip and said operating member having a head forming a seat for one end of said helical spring, a member secured to said support 5 having a head forming a seat for the other end of said spring, a second conducting strip secured by said member to said support, a flexible conductor connecting said strips, a stationary contact secured to said support in position to be 10 engaged by said movable contact when said operating member is moved to its closed circuit position.

3. A switch comprising an operating member made of insulating material, a support, means 15 pivotally mounting said member on said support, a handle on said member, a projection on said member adjacent said pivot, a cantilever spring member adjacent the end of said projection, a link member interposed between said projection 20 and said spring so as to form therewith a snap acting toggle for moving said member between its open and closed circuit positions with a snap action, a switch contact, a conducting strip supporting said contact, a second spring mounted 25 between said member and said support for holding said strip on said operating member, said second spring being weaker than said first spring, a second conducting strip, a flexible conductor connecting said strips, conducting means forming 30 a terminal for securing said second spring and said second strip to said support, and a stationary contact secured to said support in position to be engaged by said movable contact when said operating member is moved to its closed 35 circuit position.

4. A switch comprising an operating member, a support, means pivotally mounting said member on said support for pivotal movement between open and closed circuit positions, a handle on said 40 member, a projection on said member adjacent said pivot, a spring member adjacent said projection, a member interposed between said projection and said spring member and forming therewith a snap acting toggle for moving said member between its open and closed circuit positions with a snap action, a switch contact, a conducting strip supporting said contact, a projection on said operating member forming a bearing for said strip, a second spring between said operating 45 member and said support for holding said strip on said operating member, a stationary contact secured to said support in position to be engaged by said movable contact when said operating member is moved to its closed circuit position, said strip moving on said projection as a pivot against the force applied by said second spring to provide a wiping action upon engagement of said contacts.

5. A switch comprising an operating member, 50 a support, means pivotally mounting said member on said support, for pivotal movement between open and closed circuit positions, a handle on said member, a projection on said member adjacent said pivot arranged to engage said support when said member is in its open circuit position, a spring member adjacent the end of said projection, a link member interposed between said projection and said spring and forming therewith a snap acting toggle for moving said member between its open and closed circuit positions with 55 a snap action, a switch contact, a conducting strip supporting said contact, said strip being

provided with a recess forming a bearing, a projection on said operating member engaging said bearing, a second spring between said operating member and said support for holding said strip on said operating member, a stationary contact 5 secured to said support in position to be engaged by said movable contact when said operating member is moved to its closed circuit position, said conducting strip moving on said projection as a pivot upon engagement of said contacts to 10 provide a wiping action.

6. A switch comprising an operating member made of insulating material, a support, means pivotally mounting said member on said support, a handle on said member, a projection on said member adjacent said pivot, a spring member adjacent the end of said projection, a link member interposed between said projection and said spring so as to form therewith a snap acting toggle for moving said member between its open and closed 20 circuit positions with a snap action, a switch contact, a conducting strip supporting said contact, a projection on said member forming a bearing for said strip, a spring mounted between said member and said support for holding said strip 25 on said member, a second conducting strip, a flexible conductor connecting said strips, electrically conducting means forming a terminal for securing said spring member and said second strip to said support, a stationary contact secured 30 to said support in position to be engaged by said movable contact when said operating member is moved to its closed circuit position, said conducting strip moving on said projection as a pivot upon engagement of said contacts to provide a 35 wiping action.

7. A switch comprising an operating member made of insulating material, a support, means pivotally mounting said operating member on said support in substantially parallel relation 40 therewith for pivotal movement between open and closed circuit positions, a handle on said operating member, a projection on said operating member adjacent said pivot arranged to engage said support when said operating member is in 45 its open circuit position, a spring member having one end adjacent the end of said projection, a bolt extending through said support securing the other end of said spring to said support, a link member interposed between said adjacent ends of 50 said projection and said spring and forming therewith a snap acting toggle for moving said operating member between its open and closed circuit positions with a snap action, a switch contact, a conducting strip supporting said contact, 55 said strip being provided with an intermediate recess forming a bearing, a projection on said operating member engaging said bearing, a helical compression spring mounted between said operating member and said support, a pin extending 60 through said strip and said operating member having a head forming a seat for one end of said helical spring, said bolt having a head forming a seat for the other end of said spring, a second conducting strip secured by said bolt to said support, a flexible conductor connecting said strips, a stationary contact secured to said support in position to be engaged by said movable contact when said operating member is moved to its closed circuit position.

JOHN F. TRITLE.
